UNITED STATES PATENT OFFICE.

CHARLES E. ZIEGLER, OF LIMOGES, FRANCE.

DESIGN FOR A PLATE.

No. 37,794.

Specification for Design.

Patented Jan. 23, 1906.

Application filed December 18, 1905. Serial No. 292,379. Term of patent 3½ years.

To all whom it may concern:

Be it known that I, CHARLES E. ZIEGLER, a citizen of the Republic of France, residing at Limoges, Haute Vienne, France, have invented a new, original, and ornamental Design for a Plate, of which the following is a specification, reference being had to the drawings forming a part thereof.

Figure 1 is a plan of a plate, showing my

new design; and Fig. 2 is a cross-section thereof.

I claim—

The ornamental design for a plate, as shown.

CHARLES E. ZIEGLER.
